(57) **CLAIM**

The ornamental design for a vehicle, toy, and/or replicas thereof, as shown and described.

DESCRIPTION

This application contains subject matter related to the following co-pending U.S. design patent applications:

Application Ser. No. 29/456,122, filed herewith and entitled "Vehicle, Toy, and/or Replicas Thereof";
Application Ser. No. 29/456,123, filed herewith and entitled "Vehicle, Toy, and/or Replicas Thereof";
Application Ser. No. 29/456,125, filed herewith and entitled "Fairing for a Vehicle";
Application Ser. No. 29/456,126, filed herewith and entitled "Fairing for a Vehicle"; and
Application Ser. No. 29/456,128, filed herewith and entitled "Bumper for a Vehicle".

FIG. 1 is a left, front perspective view of a vehicle, toy, and/or replicas thereof according to the design;

FIG. 2 is a left side view thereof, the right side view being mirror symmetrical;

FIG. 3 is a front view thereof; and,

FIG. 4 is a top view thereof.

The broken lines are for illustrative purposes only and form no part of the claimed design.
